METAL FLASHING

Filed Aug. 12, 1931

UNITED STATES PATENT OFFICE

PEARL M. BURGESS, OF READING, MASSACHUSETTS, ASSIGNOR TO BURGESS & BLACHER CO., OF BOSTON, MASSACHUSETTS, A CORPORATION OF MASSACHUSETTS

METAL FLASHING

Application filed August 12, 1931. Serial No. 556,548.

This invention relates to metal flashings adapted to be interposed between two courses of masonry and embedded in the usual bonding or bed of mortar between said courses, the form of the flashing being such that it cooperates with the mortar in providing a mechanical bond in every direction between the flashing and the courses of masonry.

The invention relates particularly to a 10 flashing which is provided with dovetail-shaped corrugations having narrow side walls extending from one longitudinal edge of the flashing to the other, some of said walls being inclined so that they extend diagonally across the 15 layers of the masonry between which the flashing is interposed, and are non-parallel with other narrow side walls, this diagonal and non-parallel arrangement being recognized as an important factor in the production 20 of a mechanical bond in every direction between the flashing and the masonry.

Heretofore, so far as I am aware, each sheet metal section or unit of a flashing of this character has been provided with dove- 25 tail-shaped corrugations whose narrow walls, projecting from the flashing body, are, to a considerable extent, non-parallel with each other to provide a sufficient number of differently inclined or oblique walls.

30 I have found that the operation of forming non-parallel side walls on a single flashing unit requires more time and is more expensive than is the case when said side walls are parallel with each other.

35 One object of my invention is to provide an oblong flashing, having corrugated transverse zones extending crosswise of the flashing, each zone having dovetail-shaped corrugations provided with inclined narrow side walls, extending obliquely crosswise of the 40 flashing and projecting from opposite sides thereof, said walls being parallel with each other and adapted to be produced at a minimum expense, the oblique side walls of the 45 corrugations of each transverse zone being inclined oppositely to those of the next zone, to provide a mechanical bond in all directions between the flashing and the masonry. Another object is to provide an oblong sheet 50 metal flashing having a stiff longitudinal

zone stiffened by corrugations extending from one longitudinal edge partly across the flashing, and a plain longitudinal zone, having all of the inherent flexibility of the sheet metal, extending from the stiff zone to the opposite longitudinal edge, the plain zone being without corrugations so that its flexibility may be utilized as hereinafter set forth.

55 Of the accompanying drawing forming a part of this specification,—

60 Figure 1 shows in perspective, a unit constituting a member or section of a sectional elongated flashing and adapted to be assembled with a duplicate unit or units to form a 65 flashing of any desired length.

Figure 2 is a side view showing two units assembled end to end.

Figure 3 is a section on line 3—3 of Figure 2.

70 Figures 4 and 5 show in perspective a one-piece oblong flashing strip unit embodying the invention.

Figure 6 is a fragmentary perspective view illustrating a mode of using the flashing.

75 Figure 7 is a fragmentary sectional view illustrating a mode of use of the flashing shown by Figure 5.

80 Figures 8, 9 and 10 are sectional views, showing different forms of the narrow side walls of the corrugations.

85 The same reference characters indicate the same parts in all of the figures.

A flashing of average length is preferably composed of a plurality of independently formed units.

85 The unit shown by Figure 1 is independently formed from sheet metal, preferably copper, and is substantially rectangular, and constitutes a transverse zone of an elongated 90 flashing in which it is incorporated.

95 The unit has substantially parallel transverse meeting edges 12 and 13, determining the width of the flashing, and substantially parallel longitudinal edges 14, 14, collectively determining the length of the flashing when the units are assembled. The unit is provided with dovetail-shaped corrugations having narrow side walls 15, projecting from opposite sides of the unit and extending between the longitudinal edges 14. The walls 100

14 are parallel with each other and are inclined relative to the transverse edges 12 and 13, so that they extend obliquely crosswise of the unit.

8 The arrangement permits the assemblage of the units to form a flashing in which the side walls 15 of each unit are inclined oppositely to, or in a different direction from, those of the next unit, as shown by Figure 2, so that the flashing has a sufficient number of oppositely inclined edge walls 15 for all practical purposes, and may be made at a minimum cost.

15 The unit may be provided with any suitable means for securing it to another duplicate unit or units. As shown by Figure 3, each unit has a hooked seam flange 17 at one end, the flanges of the units being interengaged.

20   Each flashing unit may be made of a single oblong piece, as shown by Figure 4, the length of the piece being such that it may include a plurality of transverse zones, each zone being provided with dovetail-shaped corrugations 15 having the narrow side walls 15, projecting from opposite sides of the zone and extending obliquely crosswise of the flashing, the walls 15 in each zone being parallel with each other and having an inclination opposite that of the walls in the next zone. Figure 5 shows an oblong sheet metal piece having a stiff longitudinal zone stiffened by corrugations 15 extending from one longitudinal edge partly across the flashing, and 35 a flexible longitudinal zone 19 without corrugations extending from the stiff zone to the opposite longitudinal edge.

40 The zone 19 is adapted by its flexibility to be secured to a non-corrugated flexible supplemental flashing member 20 by a seam or joint indicated by 21 (Figure 7). The flashing may be bent to form at one longitudinal edge thereof a longitudinal flange 23, across which the corrugations extend, said flange 45 being adapted to overlap a portion of a vertical wall surface, as shown by Figure 6, and confine against said surface a portion of an angular supplemental strip 24. The side walls 15 may be variously formed, as shown by Figures 8, 9 and 10. The longitudinal zone 19 (Fig. 5) is also adapted by its flexibility to be easily bent at an angle to the stiff longitudinal zone to form a longitudinal flange arranged like the flange 23, but without corrugations, the flange being compact and having only the thickness of the sheet metal.

I claim:

60 1. An oblong flashing having a plurality of transverse zones, each zone being provided with dovetail-shaped corrugations having narrow side walls projecting from opposite sides of the zone and extending obliquely crosswise of the flashing, said walls in each zone being parallel with each other and hav-

ing an inclination opposite that of the walls in the next zone.

2. An oblong flashing as specified by claim 1, said corrugations extending from one longitudinal edge of the flashing partly to the opposite edge, so that one longitudinal edge portion of the flashing is smooth or non-corrugated and is adapted to be seamed to a non-corrugated flexible member, constituting a supplemental longitudinal edge portion of the flashing. 70 75

3. A flashing composed of a plurality of rectangular sheet metal units, each having parallel transverse meeting edges determining the width of the flashing, and parallel longitudinal edges collectively determining the length of the flashing, each unit being provided with dovetail-shaped corrugations having narrow side walls projecting from opposite sides of the unit, and extending obliquely crosswise of the flashing, said walls being parallel with each other and inclined relative to the transverse edges, the units being adapted to be assembled to form a flashing in which the side walls of the corrugations of each unit are inclined oppositely to those of the next unit. 80 85 90

4. An oblong sheet metal flashing having a stiff longitudinal zone stiffened by corrugations extending from one longitudinal edge partly across the flashing, and a flexible longitudinal zone without corrugations extending from the corrugated longitudinal zone to the opposite longitudinal edge, the flashing being adapted to be bent along the junction of the flexible zone with the stiffened zone, to convert the flexible zone into a flange arranged at an angle to the stiffened zone and having only the thickness of the sheet metal.

In testimony whereof I have affixed my signature.

PEARL M. BURGESS.
